United States Patent Office.

HENRY HOWE, OF ONEONTA, NEW YORK.

Letters Patent No. 65,913, dated June 18, 1867.

IMPROVED BOLT-TRIMMER.

The Schedule referred to in these Letters Patent and making part of the same.

TO ALL WHOM IT MAY CONCERN:

Be it known that I, HENRY HOWE, of Oneonta, Otsego county, New York, have invented a new and useful Improvement in Bolt-Trimmers; and I do hereby declare that the following is a full, clear, and exact description thereof, which will enable others skilled in the art to make and use the same, reference being had to the accompanying drawing, forming part of this specification.

This invention relates to an improvement in bolt-trimmers, and consists of two bars of iron or steel flattened at one end and pivoted together, the lower bar having a hole in its flat end to hold the nut, while the cam-shaped sharply-bevelled flat end of the upper bar is forced over it.

The accompanying drawing is a top view of my improved bolt-trimmer.

A is the lower bar, flattened at B, and having a hole to receive the nut b. C is the upper bar, flattened at D, where it is cam-shaped and sharply bevelled, and pivoted to A at d. The nut being inserted in the hole in B, is trimmed by closing the long arms, a drawing cut being given to it by the cam-shaped end D.

Having thus described my invention, what I claim as new, and desire to secure by Letters Patent, is—

The cam-shaped sharply-bevelled knife C D pivoted to and in combination with the bar A B, having a hole in B to receive the object to be trimmed by the knife C D.

HENRY HOWE.
